WRENCH SOCKET FOR VALVES AND THE LIKE

Julian W. McManus, 3733 Delmas Terrace,
Los Angeles, Calif.

Filed Mar. 27, 1962, Ser. No. 69,455

Term of patent 14 years

(Cl. D54—16)

FIG. 1.

FIG. 2.

FIG. 3.

FIG. 4.

FIG. 5.

FIGURE 1 is a perspective view showing my new design for a wrench socket for valves and the like, the side opposite being substantially the same as the side shown;

FIGURE 2 is a front view thereof;

FIGURE 3 is a side view thereof;

FIGURE 4 is a top view thereof; and

FIGURE 5 is a bottom view thereof.

I claim:

The ornamental design for a wrench socket for valves and the like, substantially as shown and described.
